UNITED STATES PATENT OFFICE.

JOHN BUNN, OF BINGHAMTON, NEW YORK, ASSIGNOR TO THE BUNN CIGAR ROLLING MACHINE COMPANY, OF SAME PLACE.

CIGAR-TIP FORMER.

SPECIFICATION forming part of Letters Patent No. 644,893, dated March 6, 1900.

Application filed September 4, 1896. Renewed January 31, 1900. Serial No. 3,520. (No model.)

To all whom it may concern:

Be it known that I, JOHN BUNN, a citizen of the United States, residing at Binghamton, in the county of Broome and State of New York, have invented certain new and useful Improvements in Cigar-Tip Formers; and I do hereby declare the following to be a full, clear, and exact description of the invention, such as will enable others skilled in the art 5 to which it appertains to make and use the same, reference being had to the accompanying drawings, which form part of this specification.

My invention relates particularly to that 15 part of a cigar-machine known as the "header" or "tip-former;" and it consists of the combination, with the header, of a positively-driven roller the periphery of which forms a movable portion of the interior wall of the 20 tip-forming chamber and one end of which is provided with a cutting edge which makes a slit in the end of the wrapper as it is being fed in and wrapped around the bunch.

My invention will be fully described in the 25 following specification and clearly defined in the subjoined claim.

Referring to the drawings, I have illustrated certain parts of a cigar-machine, including my invention, in order that the construction, location, and operation of the latter 30 may be clearly understood.

In the drawings, Figure 1 is a front elevation of my improved header, the bunch-shaping rollers and a portion of the paste-reservoir being indicated in dotted lines. Fig. 2 is a top, and Fig. 3 is a bottom, plan view of the header detached. Fig. 4 is an end view, and Fig. 5 is a horizontal section on the line $x-x$ of Fig. 4.

40 Similar reference-numerals indicate corresponding parts in each figure of the drawings.

The bunch-shaping rollers are indicated by 1 and the paste-reservoir by 2. The wrapper-stretcher is marked 3, and 4 is the header. 45 This header is provided with the usual tip-forming chamber 5 and the side opening 6 for the passage of the wrapper to the chamber. All of these parts may be of any preferred or well-known construction and form no part of 50 my present invention.

A recess 7 is formed in the lower face of the header and communicates with the tip-forming chamber 5. In the recess 7 a conical roller 8 works, said roller being carried by a shaft 9, journaled in suitable bearings 10 on 55 the header. The outer end of the shaft is provided with a pulley 11, through the medium of which the roller 8 is positively driven by means of suitable connections (not shown) to the driving mechanism of the machine. 60 The periphery of the roller 8 as it is rotated forms a movable portion of the interior wall of the tip-forming chamber 5.

It is customary in the manufacture of cigars by machines to use wrappers which are 65 already cut to the proper shape by what is known as a "wrapper-cutter," and usually it is necessary for the operator running the machine to cut with a knife the necessary slit in the end of the wrapper to enable the latter 70 to be rolled smoothly onto the tip end of the cigar. My invention is designed to render this action by the operator unnecessary, and for this purpose I form the end 12 of the roller 8 with a knife-edge, which will make the necessary slit in the wrapper as the latter is fed to the cigar-bunch, and the slit so made will 75 be in the proper position in the wrapper, which is not always the case when cut by hand.

13 indicates a passage leading to the interior of the tip-forming chamber and connected to the paste-reservoir 2 by a tube 14 in order that paste may be fed automatically to the chamber, as is common in cigar-machines.

The roller 8 is preferably driven in a reverse direction to that in which the cigar is rotated by the shaping-rollers 1.

The operation of the invention will be easily understood from the foregoing description and may be briefly stated as follows: The cigar-bunch is placed in the pocket formed by the shaping-rollers 1 with its tip end in the tip-forming chamber and is rotated by friction with the shaping-rollers. When the bunch has been rolled sufficiently, the wrapper is started into the machine and wrapped on the cigar-bunch, and when the end which goes around the tip end of the cigar comes in contact with the roller 8 the end 12 of the latter will cut the usual slit in the wrapper. 100

Having thus fully described my invention, what I claim as new, and desire to secure through Letters Patent, is—

In a cigar-machine, the combination with a cigar-header having a tip-forming chamber, of a conical roller the periphery of which forms a movable portion of the interior wall of the said chamber, the outer end of said

roller having a cutting edge to slit the wrap-
per, substantially as set forth. 10

In testimony whereof I affix my signature in presence of two witnesses.

JOHN BUNN.
